RACK AND PINION OPERATING MEANS

Elmon A. Schottenberg, Youngstown, Ohio, assignor to Truscon Steel Company, Youngstown, Ohio, a corporation of Michigan

Application October 11, 1938, Serial No. 234,486

7 Claims. (Cl. 74—33)

This invention relates to operating means for movable elements of various different kinds, and has particular reference to improvements in operating means of the type comprising a rack on the element to be moved and a pinion cooperating with said rack for moving the same and thereby moving the movable element.

While the operating means comprising the invention is capable of a wide range of uses, it has special utility as a means for opening and closing windows, doors, transoms, ventilators and the like, either singly or in banks or series. In any case, the general object of the invention is to provide an operating means of the type mentioned in which the rack is held yieldably in mesh with the pinion, whereby, in the event of obstruction to movement of the movable element while power is being applied to the pinion, or in the event of force being applied to the movable element to move same while the pinion is stationary, disengagement of the rack from the pinion will occur and damage or harm to the operating means, or to the movable element, or to whatever might obstruct movement of the movable element, thereby will be avoided. That is to say, the present invention is particularly concerned with providing a safety operator for swinging sash and the like which will prevent loss of life or injury in certain installations, and, also permit the window to be forced open from within by pressure resulting from an explosion. For example, many windows or transoms, particularly in factories or warehouses, may be operated in series or in multiple by a common operating shaft 35 driven from a motor controlled at a central station. Frequently the windows may open out on to a roof, and if a man is cleaning the inside of the windows while he is standing on the roof, it is possible that someone at the control station 40 may set the closure operating means in motion, not knowing the position of the man at work, and trap him or push him into the space below. If that contingency occurs with the present invention, the man can resist the closing of the 45 window causing the rack to slip relative to the pinion regardless of the force applied to the rack by the closure operating mechanism and thus not be injured.

On the other hand, if all of the windows are closed and a pressure exists within the place where the windows are installed, the force of the explosion can push the windows open without damage or injury to the glass in the sash, and, also, tend to prevent excessive injury to the plant 50 or shop as well as its occupants. In this aspect

the invention has particular application to installations in places where chemicals frequently explode in the sense that they create excessive gas pressures, which while not sufficient to wreck the entire building, often blow out many panes 5 of glass if the window is stationary.

A special object of the invention is to provide a simple, practical means for holding the rack yieldably in mesh with the pinion and to embody in said means provision for regulating the yieldability thereof, thereby to adapt the operating means best to serve its purpose in various different installations of the same.

Another special object of the invention is to provide, for optional use with the yieldable rack holding means, simple means for locking the rack against disengagement from the pinion in any desired position of the rack relative to the pinion, thus to lock the movable element against movement from any desired position thereof so long as the pinion remains stationary.

Another special object of the invention is to provide a locking means as stated which becomes operative automatically responsive to movement of the movable element to a selected position by actuation of the pinion.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the accompanying drawings, wherein like characters of reference denote corresponding parts in the different views:

Figure 1 is a transverse section through a portion of a window or ventilator equipped with operating means constructed in accordance with one practical embodiment of the invention, the parts of the operating means being shown in their normal, operative positions.

Figure 2 is a view similar to Fig. 1 illustrating an abnormal position of the parts of the operating means.

Figure 3 is a plan view of a portion of the operating means.

Figure 4 is a cross section on the line 4—4 of Fig. 1.

Figure 5 is a cross section on the line 5—5 of Fig. 1.

Figure 6 is a cross section on the line 6—6 of Fig. 1.

Figure 7 is a view similar to Fig. 1 illustrating

a locking element associated with the operating means; and

Figure 8 is a perspective view of the locking element.

- 5 While the present operating means may, as aforesaid, be employed for operating various different movable elements, it has special utility when employed for operating windows, ventilators and the like. Accordingly, there is illustrated in the 10 present instance a movable element in the form of a window or ventilator, designated as 10, which is assumed to be hinged for inward and outward movement between closed and open positions. It is to be understood, however, the window illustrated merely is representative of various other movable elements which may be mounted for movement in various different ways and which may be operated by operating means embodying the features of the invention.
- 15 20 Primarily, the present operating means comprises a rack bar 11 and a cooperating pinion 12. The rack bar 11 is pivoted at one end, as at 13, to the window or other movable element 10 to be operated and the pinion 12 is fixed on a shaft 14 which is rotatable but which otherwise is stationary. Normally the teeth of the rack bar and the pinion are in mesh with each other. Consequently, rotation of the shaft and pinion in one direction is effective to shift the rack bar longitudinally in one direction to move the movable element in one direction, and rotation of the shaft and pinion in the opposite direction is effective to shift the rack bar longitudinally in the opposite direction to move the movable element in the opposite direction, all in accordance with common and well known mechanics.

Now, in accordance with the invention, the rack bar 11 is urged toward and is maintained normally in mesh with the pinion 12 by yieldable means. In this connection it is, of course, inherent to a rack and pinion operating means, due to the wedging cooperation of the teeth of the rack and pinion, that rotation of the pinion, or longitudinal movement of the rack, tends to move the rack away from the pinion. Consequently, if, during rotation of the pinion in either direction to move the movable element in either direction, movement of the movable element should, for any reason be obstructed, the rack bar is free to move away from or to be disengaged from the pinion and the latter is free to continue rotating without damaging or harming the operating means, the movable element or whatever may be obstructing movement of the latter. Moreover, should the pinion be held against rotation and should there be applied to the movable element a force sufficiently strong to move same, the same result will occur; viz., the rack bar first will be moved away from and then harmlessly across the pinion and damage to the movable element or to the operating means will not occur. In various manufacturing plants explosions are not uncommon, and air pressure due to an explosion is an example of a force which might act upon a movable element in the form of a window, ventilator or the like to move the same while the pinion is stationary.

The particular means illustrated in the present instance for yieldably urging the rack bar 11 toward and maintaining it normally in mesh with the pinion 12, comprises a U-shaped yoke 15 embracing the hub of the pinion 12 or, alternatively, the shaft 14, and rockable with respect thereto; a roller 16 mounted on a pin 17 carried by one of the arms 18 of said yoke and engaging the edge

of the rack bar 11 remote from the pinion 12; a rocker arm 19 pivotally connected at one end with the arm 18, preferably through the instrumentality of the pin 17, and overlying the edge of the rack bar 11 remote from the pinion 12 and having its other end extending beyond the other arm 20 of the yoke 15; a roller 21 carried by the last mentioned end of said rocker arm and also engaging the edge of the rack bar remote from the pinion; and a spring 22 reacting from the arm 20 of the yoke 15 upon the second mentioned end of the rocker arm 19, thereby urging the latter constantly toward the rack bar and tending to rock the yoke to maintain the roller 16 engaged with the rack bar and, consequently, urging the rack bar constantly toward or into mesh with the pinion 12. In other words, whether the yoke directly embraces the hub of the pinion 12 or the shaft 14, the spring 22 reacts from said shaft through the yoke upon the rack bar to maintain the latter normally in mesh with the pinion.

Obviously, if the rack bar 11 is held against movement because of an obstruction to movement of the movable element 10 and if, at the same time, the pinion 12 is rotated, the wedging coaction of the teeth of the pinion with the teeth of the rack bar will result in the rack bar being moved away from the pinion. In other words, outward pressure exerted upon the rack bar will result in a combined rocking movement of the yoke 15 about the hub of the pinion 12 or about the shaft 14, as the case may be, and outward swinging movement of the rocker arm 19 about its pivot 17, all against the force of the spring 22, until the teeth of the rack bar are completely disengaged from the teeth of the pinion. Accordingly, if the pinion continues to rotate it will be ineffective to move the rack bar. If, then, rotation of the pinion 12 ceases, the spring 22 obviously will act to restore the parts to their normal positions in which the teeth of the rack bar are in mesh with the teeth of the pinion. On the other hand, if the pinion is held against rotation as, for example, by a motor or other means employed for rotating the shaft 14, and if, at the same time, a force is exerted upon the movable element 10 to move the same, the same ultimate result as just described will occur, the only difference being that separation of the rack bar from the pinion will take place due to longitudinal movement of the rack bar.

Preferably means is provided to regulate the compression or force normally exerted by the spring 22 so as to predetermine the amount of resistance that must be offered to longitudinal movement of the rack bar 11 when the pinion 12 is rotated, and to predetermine the force which must be exerted longitudinally upon the rack bar when the pinion is held against rotation, to effect disengagement of the rack bar from the pinion. In the present instance this means comprises a screw 23 threaded into the arm 20 of the yoke 15 and constituting an adjustable stop or abutment for the outer end of the spring 22. Obviously, by adjustment of said screw the force of the spring may be varied to best adapt the operating means to function under various different conditions of installation of the same.

Preferably means also is provided to positively limit outward or disengagement movement of the rack bar 11 relative to the pinion 12. In the present instance this means comprises a strut element 24 interposed between the rocker arm 19 and an outer end portion of the arm 20 of the

yoke 15, said strut element being in the form of a tube engaged over the screw 23 and the spring 22 whereby it is held in place by the former and serves as a protective shield for the latter.

5 While the yoke 15 may be of any suitable construction, it preferably is formed from a single length of stock material bent to provide the arms 18 and 20 each comprised by opposite side portions spaced apart to accommodate therebetween the rack bar 11 and the pinion 12. Accordingly, when the yoke is assembled with the rack and the pinion it is held operatively positioned by the latter.

As in the case of the yoke 15, the rocker arm 19 may be of any suitable construction. Preferably, however, said rocker arm is formed from suitable sheet material bent into U-shape cross sectionally whereby it is both light and strong, there being preferably a tongue 25 struck outwardly from its 20 bottom wall to enter the inner end of the spring 22 and to serve as a centering and holding means for the said inner end of said spring.

Under some conditions of installation of the operating means it may be desirable to provide 25 means to lock the rack bar against separation from the pinion when the movable element is in some predetermined position, thus to lock the movable element in its predetermined position. For example, when the movable element is in the 30 form of a window or ventilator it may be desirable to provide means to lock the same in a closed position. A simple means for this purpose, automatically operable upon operation of the operating means to move the movable element to a 35 predetermined position, may comprise a cam element 26 to be mounted on the rack bar 11 to engage the roller 21 to lift the rocker arm 19 to its limit of outward swinging movement, as determined by the strut element 24, when the movable 40 element has reached its predetermined position. Obviously, when the cam element 26 is in a position holding the rocker arm 19 at or near its limit of outward swinging movement it is not possible, by longitudinal movement of the rack 45 bar, to effect disengagement of the rack bar from the pinion 12. Accordingly, the movable element is locked against movement insofar as concerns any force acting directly upon the movable element or the rack bar. Therefore, the movable 50 element can be moved only by rotation of the pinion 12.

As illustrated in the present instance the cam element 26 may appropriately comprise a blade-like portion to rest against the edge of the rack bar 11 remote from the pinion 12 and having an inclined end to cause the roller 21 to ride upon the top thereof when the rack bar reaches a predetermined position relative to the pinion; while to facilitate fastening of said cam element to the rack bar said element may be provided with arms 27 to straddle the rack bar and to have passed through any of a plurality of pairs of holes 28 therein a bolt 29 to lie in the space between a selected pair of teeth of the rack bar, thereby to hold said element in assembly with the rack bar and against longitudinal movement relative thereto.

Manifestly, one of the present operating means may be employed for operating only a single 70 movable element, or a plurality of said operating means, to which a shaft 13 is common, may be employed for operating a plurality of movable elements. In either case, the shaft 13 may be manually rotatable by any suitable means, such 75 as a crank, or it may be motor driven.

In any case where a plurality of the operating means are employed in association with a single shaft 13 for the operation of a plurality of movable elements, the teeth of the rack bars may be so terminated as to cause all of the movable elements to assume desired similar positions upon actuation of the shaft 14 and pinions 12. For example, the last tooth x may have a plain portion y adjacent thereto which permits the actuating mechanism to urge all of the closures to their 10 open position for picking up the teeth which are out of line and aligning the complete series for closing.

Without further description it is thought that the features and advantages of the invention will 15 be readily apparent to those skilled in the art, and it will, of course, be understood that changes in the form, proportion and minor details of construction may be resorted to, without departing from the spirit of the invention and scope of the 20 appended claims.

I claim:

1. In a window operator, a rack bar, a pinion, a shaft carrying said pinion, a yoke supported by said shaft and having a pair of arms extending 25 across said rack bar at points spaced longitudinally therealong, a roller carried by one of said arms and engaging the edge of the rack bar remote from the pinion, a rocker arm pivotally connected at one end to said yoke arm, and ex- 30 tends at its other end toward the other yoke arm, a roller on said rocker arm spaced from said first mentioned roller and engaging the edge of the rack bar remote from the pinion, and a spring reacting from the second mentioned arm 35 of the yoke upon said rocker arm to urge the latter toward the rack bar.

2. In a window operator, a rack bar, a pinion, a shaft carrying said pinion, a yoke supported by said shaft and having a pair of arms extending 40 across said rack bar at points spaced longitudinally therealong, means carried by one of said arms engaging the edge of the rack bar remote from the pinion, a rocker arm pivotally connected at one end to said yoke arm and ex- 45 tends toward the other yoke arm, means on said rocker arm spaced from said first mentioned yoke arm and engaging the edge of the rack bar remote from the pinion, and spring means reacting from the second mentioned yoke arm upon 50 said rocker arm to urge the latter toward the rack bar.

3. In a window operator, a rack bar, a pinion, a shaft carrying said pinion, a yoke supported by said shaft and having a pair of arms extending 55 across said rack bar at points spaced longitudinally therealong, means carried by one of said arms engaging the edge of the rack bar remote from the pinion, a rocker arm pivotally connected at one end to said yoke arm and extending toward 60 the other yoke arm, means on said rocker arm spaced from said first mentioned yoke arm and engaging the edge of the rack bar remote from the pinion, an element mounted in the second mentioned arm of said yoke for inward and outward adjustment relative thereto, and spring means reacting from said element upon said rocker arm to urge the latter toward the rack bar. 65

4. In a window operator, a rack bar, a pinion, a shaft carrying said pinion, a yoke supported by 70 said shaft and having a pair of arms extending across said rack bar at points spaced longitudinally therealong, means carried by one of said arms engaging the edge of the rack bar remote from the pinion, a rocker arm pivotally con- 75

5
6 nected at one end to said yoke arm and extending toward the other yoke arm, means on said rocker arm spaced from said first mentioned yoke arm and engaging the edge of the rack bar
7 remote from the pinion, spring means reacting from the second mentioned yoke arm upon said rocker arm to urge the latter toward the rack bar, and means interposed between said rocker arm and the second mentioned yoke arm to positively limit movement of the rack bar away from the pinion.

8 5. In a window operator, a rack bar, a pinion, a shaft carrying said pinion, a yoke supported by said shaft and having a pair of arms extending across said rack bar at points spaced longitudinally therealong, a roller carried by one of said arms and engaging the edge of the rack bar remote from the pinion, a rocker arm pivotally connected at one end to said yoke arm, and extending at its other end beyond the other yoke arm, a roller on the last mentioned end of said rocker arm engaging the edge of the rack bar remote from the pinion, a screw threaded in the second mentioned yoke arm for inward and outward adjustment relative thereto, and a spring reacting from said screw upon said rocker arm to urge the latter toward the rack bar.
9 6. In a window operator, a rack bar, a pinion, a shaft carrying said pinion, a yoke supported by said shaft and having a pair of arms extend-

10 5
11 ing across said rack bar at points spaced longitudinally therealong, a roller carried by one of said arms and engaging the edge of the rack bar remote from the pinion, a rocker arm pivotally connected at one end to said yoke arm, and extending at its other end beyond the other yoke arm, a roller on the last mentioned end of said rocker arm engaging the edge of the rack bar remote from the pinion, a screw threaded in the second mentioned yoke arm for inward and outward adjustment relative thereto, a spring reacting from said screw upon said rocker arm to urge the latter toward the rack bar, and a tubular strut element between the rocker arm and an outer end portion of the second mentioned yoke arm for limiting outward movement of the rack bar relative to the pinion, said strut element being disposed in protective surrounding relationship to said spring and being engaged over said screw whereby it is retained in operative assembly with the yoke and the rocker arm.

12 6
13 7. The combination as set forth in claim 1 including means on the rack bar for engagement with the roller on the rocker arm to move said rocker arm to a position locking the rack bar against movement away from the pinion when the rack bar reaches a predetermined position relative to the pinion.

14 ELMON A. SCHOTTENBERG. 30
